UNITED STATES PATENT OFFICE.

ELMER L. FEES, OF PLEVNA, KANSAS.

WASHBOARD.

1,173,940.

Specification of Letters Patent. Patented Feb. 29, 1916.

Application filed April 11, 1914. Serial No. 831,192.

To all whom it may concern:

Be it known that I, ELMER L. FEES, a citizen of the United States, residing at Plevna, in the county of Reno and State of Kansas, have invented new and useful Improvements in Washboards, of which the following is a specification.

This invention relates to washboards and especially to self-soaping washboards.

10 The invention has for its object to produce a self-soaping washboard of simple and improved construction having a soap compartment and a grooved roller forming the bottom of such compartment and capable of being rotated by frictional contact with the garments that are being washed so that it will operate to transfer such from the compartment to the garments.

Further objects of the invention are to 20 simplify and improve the general construction of the washboard.

With these and other ends in view which will readily appear as the nature of the invention is better understood, the same 25 consists in the improved construction and novel arrangement and combination of parts which will be hereinafter fully described and particularly pointed out in the claim.

In the accompanying drawing has been 30 illustrated a simple and preferred form of the invention, it being, however, understood that no limitation is necessarily made to the precise structural details therein exhibited, but that changes, alterations and 35 modifications within the scope of the claim may be resorted to when desired.

In the drawing, Figure 1 is a front view of a washboard constructed in accordance with the invention. Fig. 2 is a sectional 40 view taken on the line 2—2 in Fig. 1. Fig. 3 is a side view. Fig. 4 is a sectional detail view taken on the line 4—4 in Fig. 1.

Corresponding parts in the several figures are denoted by like characters of reference.

45 The frame of the improved washboard comprises the side members 15, the cross bar or bottom brace 16, the cap piece 17 and the back 18, the latter being secured on the side members 15 near the upper ends of the 50 latter. The portions of the side members that extend below the cross bar 16 constitute the legs of the washboard, and said legs are provided with slidable extension members, each consisting of a bar 19 having a slot 20. Each extension member is guided for slidable movement in a keeper 21 on the

side member of the frame. Each side member is provided near its lower end with a rock shaft 22 having at one end a handle 23, whereby it may be oscillated and at the other end a T-head 24 operating in the slot 20 of the extension member and so proportioned that when positioned at right angles to the slot, it will frictionally engage the side walls thereof and thus serve to maintain the extension member in adjusted position.

The side members 15 are connected together approximately in the plane of the lower edge of the back 18 by a cross bar 25, 70 the latter being well spaced from the lower end portion of the back member. Supported for rotation directly below the cross bar 25 and in such a position as to extend beneath the open space between said cross bar and the 75 back member is a roller 26 having spirally disposed grooves or depressions 27 which may be arranged spirally, as shown, or in any other desirable and convenient manner. A cross bar 28 connects the side members 15 80 about midway between the upper and lower ends of the back member 18, said cross bar being reinforced by brackets 29. The side members are each provided with a pair of cleats 30 constituting guideways for a slide- 85 able cover member 31 which constitutes a lid or cover for the soap compartment, which latter is included between the side members, the cross bar 28 and the lower portion of the back member 18 and the portion of the roller 90 26 which extends beneath the open space between the cross bar 25 and the back member 18. The cover member 31 is transversely corrugated so that when in obstructing position with respect to the soap compartment, 95 it will constitute a portion of the rubbing surface of the washboard. One or more bars of soap may be placed in the compartment just referred to, and a loose weight member 32 may be provided to assist in feeding the 100 soap in the direction of the roller. The space above the cross bar 28 may be utilized for bars of soap held in reserve. It will be seen that the roller 26 has a substantially smooth surface which is merely provided with 105 spirally disposed grooves or depressions adapted to be filled with soap to be transferred to the clothes that are to be washed. The movable cover member 31, which slides vertically in the direction of the roller and 110 the lower edge of which contacts with the roller when the cover member is in obstruct-

ing position will, therefore, not interfere with the free rotation of the roller by engagement of the latter with the clothes that are being rubbed upon the washboard and which 5 pass in engagement with said roller. A longitudinally grooved roller, or one provided with projections on the face thereof, would obviously be inoperative in connection with the vertically slidable cover member.

10 The side members may be provided on their inner faces with cleats 33 between the roller 27 and the cross bar 16 to support the customary corrugated face plate 34 which 15 may be made of zinc or other material. This face plate taken in connection with the corrugated cover member 31 forms an extended rubbing surface, a portion of which is positioned below the corrugated roller, while another portion thereof is located above said 20 roller, which latter supplies soap to garments that are passed over the same in either direction, upwardly or downwardly. Cleats 35 are secured on the rear side of the washboard, said cleats being spaced from the rear faces of the uprights or side members 15 by the back member 18 at their upper ends and at their lower ends by spacing strips or members 36. These cleats serve as guards 25 for the corrugated roller 26 to prevent any possibility of said roller contacting with the tub or with other obstructions which would by frictional engagement therewith prevent it from rotating freely when in operation. 30 They do not, however, completely cover the roller in such a manner as to prevent water having access to the rear as well as the front portion of said roller, which is obviously desirable in order that the best results may be 35 attained.

40 From the foregoing description, taken in connection with the drawings hereto annexed, the operation and advantages of this invention will be readily understood. The leg extension members will enable the board to be utilized in a deep tub when it may be raised or elevated to a convenient position

45 for operation. Said extension members may also serve to support the washboard at various angles, assuming the said extension members to be placed in engagement with the angle between the bottom of the tub and the wall portion thereof. By rubbing the garments over the roller, the latter will be rotated, and by engagement with the soap the 50 grooves of said roller will become more or less filled with soap which will thus be conveyed into engagement with the garments. To regulate the use and to avoid waste of soap, the operator, by pressing the slidable 55 cover member 30 downwardly against the circumference of the roller, may partly obstruct or entirely prevent the rotation of said roller, the member 30 acting as a brake by the lower edge thereof contacting with the 60 surface of the roller.

Having thus described the invention, what is claimed as new, is:—

65 In a washboard, a frame having side members, a top member and a back member, a roller supported for rotation closely adjacent to the lower edge of the back member, a corrugated plate secured with its upper edge in proximity to the lower forward portion of the roller, said plate constituting a stationary rubbing surface, cleats secured on the inner faces of each of the side members above the roller, and a corrugated cover member 70 constituting a rubbing surface guided slidably by the cleats and normally contacting the upper forward portion of the roller, said side members, back member and cover member combining with the roller to constitute a soap receptacle, and said roller being provided with spirally disposed 75 soap receiving grooves or indentations in the surface thereof.

80 In testimony whereof I affix my signature in presence of two witnesses.

ELMER L. FEESE.
